AUTOMATIC THREADING SHUTTLE

Edward C. Nichols, Upton, Mass., assignor to
Draper Corporation, Hopedale, Mass., a corpora-
tion of Maine

Application May 13, 1944, Serial No. 535,451

7 Claims. (Cl. 139—217)

The present invention relates generally to automatically threading shuttles for looms and, as illustrated herein, relates more particularly to means for maintaining a uniform tension on the filling thread as it runs through the shuttle.

Tension devices in the form of spring clamps are being used extensively in shuttles to exert tension on the filling thread as it runs out of the shuttle. Usually such tension devices comprise a single pair of tension pads which are urged toward each other by a coiled spring which bears at one end against one of the pads and at its other end against the end of an adjusting screw. A single pair of tension pads is not entirely satisfactory since an even and uniform pressure may not always be applied to the filling thread. For example, if the thread is of uneven diameter, the passage of a thickened portion will cause separation of the pads and the pads ordinarily cannot move toward each other quickly enough to engage the filling thread as the diameter thereof abruptly decreases. As a result little or no tension is applied to the filling thread under such conditions. Thus wide variation of tension is applied to the filling thread and wide variation in the appearance of the filling thread in the woven cloth will follow particularly when filling thread of rayon or other synthetic material is being used.

To avoid such wide variation of tension when uneven filling is being woven, two pairs of tension pads or clamping devices are used and since one of these pairs of pads will always engage the filling thread such wide variation of tension cannot occur. It was found, however, to be difficult to maintain a uniform clamping pressure since the spring adjusting screws would loosen during operation of the shuttle.

To this end and in accordance with one object of the invention, the present threading block is provided with resilient means which is caused to engage and bear against the adjusting screws for the tension springs and which resilient means is held in pressure engagement with said screw by a single adjustable member. Thus both screws are held in adjusted position and the tension on the pads is maintained as desired.

As illustrated, the screw holding or locking means comprises a relatively stiff spring wire which is deformed and caused to bear against the exposed portions of the spring adjusting screws by means of a single screw engaging the wire between the two adjusting screws. By this construction, substantial pressure may be applied to the wire and to the spring adjusting screws by a single screw, thus providing an effective and simple locking device.

With the above and other objects and features in view the invention will now be described with particular reference to the accompanying draw-

ing which illustrates a preferred embodiment of the invention and in which:

Fig. 1 is a plan view of the end of a shuttle having the present invention embodied therein;

Fig. 2 is a plan view, on a somewhat enlarged scale, of the threading block shown in Fig. 1;

Fig. 3 is a sectional view taken substantially along the line III—III of Fig. 2; and

Fig. 4 is a sectional view taken substantially along the line IV—IV of Fig. 2.

The shuttle shown in the drawing comprises a shuttle body 10 having a cavity 12 for receiving an automatically replaceable filling carrier such as a bobbin 14. The shuttle is also provided with a recess 16 communicating with the cavity 12 and which receives a threading block 18 which delivers the filling thread F to a side delivery eye 20.

The shuttle has a longitudinally extending thread passage 22 which is in alignment with the cavity 12. The thread passage extends into and through the threading block 18 and is defined by the rear wall 24 and the front wall 26 of the threading block. A horn 28 projects outwardly and rearwardly to the outer end of the rear wall 24. The threading block 18 disclosed herein is substantially the same as the one disclosed in an application for United States Letters Patent, Serial No. 459,795, filed September 26, 1942, in the name of James Gardiner Allen, now Patent No. 2,350,307, to which reference may be had for a detailed description of those elements which are not necessary to a complete understanding of the present invention and which are not described herein.

The present threading block 18, as illustrated, is provided with two sets of tension pads 30, 32. These pads are spring urged toward each other to apply tension to the filling F as it runs through the threading block and since both of these sets of pads are identical only one set will be described.

The pads 32, as shown best in Fig. 4, are each provided with a laterally extending portion 34 which fits into a hole 36 formed in the front and rear walls of the threading block 18. These laterally extending portions prevent displacement of the upper ends of the pads and displacement of the lower ends of the pads is prevented by a pin 38 extending through the front and rear walls of the threading block and through the pads, as is usual in tension pads of this type. The pads 32 are spring urged toward each other by compression springs 40 and the tension of each spring is adjusted by means of members 42 which are screw threaded into openings 44 formed in the front and rear walls of the threading block 18. Thus the members 42 may be rotated to increase or to decrease the tension on the springs 40.

In order to prevent undesired or accidental ro-

tation of the screw member 42, means is provided which engages and applies a friction drag to the screw members 42. As shown, most clearly in Fig. 3, a hole 46 is drilled longitudinally of the block 18 and which intersects the openings 44 and thus exposes a portion of the screw threaded members 42. The drilled hole 46 is of relatively large diameter and receives a wire 48 which fits into a small drilled hole which terminates in a larger drilled hole 50. The hole 50 is of sufficient size to receive a tool for bending the end of the wire 48, as shown best in Fig. 2, to hold the wire in position in the hole 46.

The wire 48 is deflected downwardly as shown in Fig. 3 by a screw 52 threaded in a vertical hole 54 formed in each of the front and rear walls of the thread block 18. The wire 48 is preferably formed of spring steel and thus bears quite strongly against the exposed portions of the threaded members 42 when the screw 52 is driven home to press the wire against the bottom wall of the hole 52 and between the members 42. The pressure of the wire 48 against each of the members 42 is sufficient to prevent rotation of said members 42 due to impact and vibration which may be set up during normal operation of the shuttle. The pressure of the wire 48 is substantially equal on each of the members 42 and since this equal pressure is obtained by turning a single screw 52, it is evident that an effective and simple means has been provided for preventing undesired or accidental rotation of the screw members 42.

Having thus described a preferred embodiment of my invention what I claim as new and desire to secure by Letters Patent of the United States is:

1. An automatically threading loom shuttle having a cavity for a filling carrier, a threading block having a longitudinally extending thread passage in alinement with said cavity, tension means in said passage comprising pairs of opposed friction members extending transversely of said thread passage, means associated with each of said pairs of friction members for yieldingly pressing said friction members of each pair together, means for separately adjusting the pressure of each of said pairs of pressing means, and a common locking means engaging said adjusting means, and a single member engaging said common locking means for locking said adjusting means in adjusted position.

2. An automatically threading loom shuttle having a cavity for a filling carrier, a threading block having a longitudinally extending thread passage in alinement with said cavity, tension means in said passage comprising two pairs of friction members extending transversely of said passage means associated with one member of each pair for yieldingly pressing said one member against the other member, means for adjusting the pressure of each of said pressing means, and a single member arranged to engage both of said adjusting means, and a member for applying tension to said single member for locking said adjusting means in adjusted position.

3. An automatically threading loom shuttle having a cavity for a filling carrier, a threading block having a longitudinally extending thread passage in alinement with said cavity, tension means in said passage comprising two pairs of opposed friction members extending transversely

of said passage, each of said pairs of friction members including a spring bearing against one of said members to apply tension to a filling thread located therebetween, an adjusting member for each spring and for controlling the pressure of each spring, means engaging said adjusting members, and a single member for pressing said last mentioned means into locking engagement with said adjusting members.

4. An automatically threading loom shuttle having a cavity for a filling carrier, a threading block having a longitudinally extending thread passage in alinement with said cavity, tension means in said passage comprising two pairs of opposed friction members extending transversely of said passage, a pair of springs each bearing against one of the friction members of each pair, a pair of screw threaded adjusting members for varying the tension of each of said springs, means engaging each of said adjusting members, and a single means for moving said engaging means into locking engagement with said screw threaded adjusting members.

5. An automatically threading loom shuttle having a cavity for a filling carrier, a threading block having a longitudinally extending thread passage in alinement with said cavity, means in said passage for applying tension to a filling thread, said means comprising two pairs of friction members extending transversely of said passage, a spring associated with each of said pairs of friction members for applying pressure directly to one friction member of each pair, a threaded member associated with each of said springs for adjusting the tension of each of said pair of friction members, a locking member arranged to engage said threaded members, and means for engaging said locking member intermediate its ends to apply locking pressure thereto.

6. An automatically threading loom shuttle having a cavity for a filling carrier, a threading block having a longitudinally extending thread passage in alinement with said cavity, tension means in said passage, said tension means comprising two pairs of friction plates having contacting friction faces, springs arranged to engage one plate of each pair to said plate against the other plate of the pair, an adjusting screw bearing against one plate of each pair for adjusting the tension of said springs, means in said block arranged to engage said adjusting screws, and a single member arranged to engage said last mentioned means for applying pressure thereto to lock said screws in adjusted position.

7. An automatically threading loom shuttle having a cavity for a filling carrier, a threading block having a longitudinally extending thread passage in alinement with said cavity, tension means in said passage, said tension means comprising two pairs of friction plates having contacting friction faces, springs arranged to engage one plate of each pair to said plate against the other plate of the pair, a pair of adjusting screws threaded into said threading block for adjusting the tension of said springs, a wire member in an opening in said block located transversely of said screws and arranged to engage said screws, and a locking screw arranged to engage said wire member intermediate its ends for applying locking pressure to said adjusting screws.
